UNITED STATES PATENT OFFICE.

ÁRON KOVÁCS, OF NEW YORK, N. Y.

DOOR-HANGER.

1,070,488.

Specification of Letters Patent. Patented Aug. 19, 1913.

Application filed November 11, 1912. Serial No. 730,668.

To all whom it may concern:

Be it known that I, ÁRON Kovács, a subject of the King of Hungary, residing at New York, in the county of New York and 5 State of New York, have invented certain new and useful Improvements in Door-Hangers, of which the following is a specification, reference being had therein to the accompanying drawing.

10 This invention relates to door hangers, and the primary object of my invention is to provide a telescopic hanger that permits of a door being easily and quickly opened and closed, the hanger being compact and 15 presenting a neat and attractive appearance in connection with a door.

Another object of this invention is to provide a door hanger with anti-frictional rollers that permit of a door being easily and 20 safely shifted from one position to another.

A further object of this invention is to accomplish the above results by a mechanical construction that is applicable to various 25 kinds of buildings, durable, easy to construct and highly efficient as a movable support for a suspended door.

With the above and other objects in view the invention resides in the novel construction, combination and arrangement of parts 30 to be hereinafter specifically described and then claimed.

Reference will now be had to the drawing, wherein:—

Figure 1 is a side elevation of a door 35 hanger in accordance with this invention, Fig. 2 is a longitudinal sectional view showing the hanger in an extended position, Fig. 3 is a similar view of a hanger casing, Fig. 4 is an end view of the same, Fig. 5 is a 40 side elevation of the inner section of the hanger member, Fig. 6 is an end view of the inner section of a hanger member, Fig. 7 is an enlarged cross sectional view of the hanger, and Fig. 8 is a perspective view of 45 a detached stop.

A door hanger in accordance with this invention includes a stationary hanger casing and a hanger section formed of an inner and an outer longitudinally shiftable section.

50 The hanger casing comprises an oblong body having side walls 1 and 2 and end wall 3 and a top plate 4. The top plate 4 has the inner side thereof provided with recesses 5 and extending into said recesses are 55 revoluble anti-frictional rollers 6 that are

supported by plates 7 countersunk in the top plate 4. The anti-frictional rollers are equally spaced throughout the length of said top plate. The side walls 1 and 2 are provided with inwardly projecting ledges 8 forming a longitudinal slot 9 and said ledges have anti-friction rollers 10 similar to the rollers 6.

The inner longitudinally shiftable section 65 of the hanger member is slidably mounted in the casing between the rollers 6 and 10, said section comprising side walls 11, a top plate 12 engaging the rollers 6, an end wall 13 and a longitudinal strip 14 that provides 70 two longitudinal slots 15. The side walls 11 are movably supported by the rollers 10 and one of said side walls is slotted, as at 16 to receive a stop 17 that is movably mounted upon the end of a screw 18. The side wall 75 2 of the casing is slotted, as at 19 whereby the stop can be placed in an opening 20 at one end of the slot, shifted to the opposite end of the slot and then the screw 18 tightened to hold the stop relatively to the casing, whereby said stop will limit the movement 80 of the inner hanger section.

Movably mounted upon the strip 14 of the inner section is the outer longitudinally shiftable section of the hanger member 85 which comprises a bar 21, straps 22, a door support 23 and a head 24. The bar 21 has the inner end thereof provided with an anti-friction roller 25 that moves upon the strip 14 and said bar furthermore travels upon an 90 anti-friction roller 26, carried by a block 27 at the outer end of the inner hanger section. The bar 21 has a depending pin 28 that engages the inner section of the hanger member 95 and limits the movement of the outer section of the hanger member.

From the foregoing it will be observed that the sections can be easily extended or shifted to be housed partially by the hanger casing, and while in the drawing there is 100 illustrated a preferred embodiment of the invention, it is to be understood that the structural elements are susceptible to such variations and modifications as fall within the scope of the appended claim.

105 What I claim is:—

A door hanger comprising a casing open at one end and having its bottom wall formed with a longitudinal slot, anti-friction rollers carried centrally of the top wall 110 of the casing and projecting into the latter, two sets of anti-friction rollers carried by

the bottom wall of the casing and projecting thereinto, an inner hanger member section mounted in said casing and traveling against said rollers and provided at its bottom with a track spaced from its sides to provide a pair of longitudinal slots, an outer hanger member section including anti-friction rollers traveling upon the said track, extending through one end of said inner section and down through the slots of said inner section and through the slot of the casing, said casing having one side wall pro-

vided with a slot, and means carried by the inner hanger member section and extending in the slot in the side wall of the casing and 15 providing means for limiting the shifting movement of said inner section.

In testimony whereof I affix my signature in the presence of two witnesses.

ÁRON KOVÁCS.
